(57) **CLAIM**

The ornamental design for a archery bow mounted flashlight holder, as shown.

DESCRIPTION

FIG. 1 is a perspective view of a archery bow mounted flashlight holder showing my new design;
FIG. 2 is a first side elevational view thereof;

FIG. 3 is a second side elevational view as seen 90 degrees from that of FIG. 2;

FIG. 4 is a third side elevational view as seen 180 degrees from that of FIG. 2,

FIG. 5 is a fourth side elevational view as seen 180 degrees from that of FIG. 3;

FIG. 6 is a top plan view thereof; and,

FIG. 7 is a bottom plan view thereof.
